(57) **CLAIM**

The ornamental design for a ceiling fan light unit with light shade, as shown and described.

DESCRIPTION

FIG. 1 is a perspective view of a ceiling fan light unit with light shade shown in use;

FIG. 2 is a greatly enlarged side view of a light unit with light shade in accordance with the present invention;

FIG. 3 is an enlarged perspective view of the light unit with light shade in accordance with the present invention; and,

FIG. 4 is an enlarged bottom view of the light unit with light shade in accordance with the present invention.

The broken line showing of a ceiling fan and of the pull chains is included for the purpose of illustrating environmental structure and forms no part of the claimed design.
